UNITED STATES PATENT OFFICE.

GEORGE HAMILTON McFEATERS, OF JOHNSTOWN, PENNSYLVANIA.

ENGINE-STOP.

1,140,694.

Specification of Letters Patent. Patented May 25, 1915.

Application filed September 25, 1908. Serial No. 454,694.

To all whom it may concern:

Be it known that I, GEORGE H. McFEATERS, of Johnstown, in the county of Cambria and State of Pennsylvania, have invented a new and useful Improvement in Engine-Stops, of which the following is a full, clear, and exact description, reference being had to the accompanying drawings, which form a part of this specification.

10 My invention has relation to automatic stops for steam engines, and particularly relates to that class of engines, known as the Corliss type.

One of the objects of my invention, is to provide a stop in which a guard member will be thrown in front of the lifting pawls which raise the crank arms, connected to the valve stems of the engine. One of these guard members is provided for the lifting pawl on each side of the cylinder of a single acting engine, and are provided for the lifting pawls on the high pressure cylinder of a compound, or triple expansion engine. These guards are rotatably mounted on the bearing for the valve stem, and when the engine is to be stopped, the guards are rotated so as to come into alinement with the lifting pawls, and prevent them from engaging and lifting the crank arm of the 30 valve stems.

Another object of my invention is, to connect these guards by means of a link, with a cross head which is connected to a movable rod held in its normal or elevated position, by mechanical or electrical means. When the rod is held in its normal position, (the running position) by means of a solenoid, the current acting thereon, would be a normally closed circuit, and when it is desired to stop the engine, the circuit is opened; and when the rod is retained in its elevated position by mechanical means, I provide an electromagnet to release the rod, and the movement of the same will rotate 45 the guards into the line of movement of the lifting pawls.

Another object of my invention is to provide various hand switches at different points throughout the power house, or plant, 50 the closing of either of the switches in this circuit releasing the rod.

Still another object of my invention is to provide an individual stop for each engine in a large power plant, in which the generators are each directly connected with their respective engines, and to so connect the various switches, that each engine can be stopped from a series of points, and throw its circuit breaker while the engine is being stopped.

I attain these various objects by the mechanism described in the annexed specification, and illustrated in the accompanying drawings, in which:

Figure 1, is a side elevation of the cylinder end of a Corliss engine with my improved stop attached; Fig. 2, is a detail side elevation of a valve stem, the guard and the lifting pawl showing the lifting pawl in engagement with the valve stem crank arm; Fig. 3, is a view similar to Fig. 2, showing the guard in alinement with the lifting pawl, to prevent the engagement of the lifting pawl with the crank arm, of the valve stem; Fig. 4, is a front view of the 75 rod releasing mechanism; Fig. 5, is a vertical section through the same.

As the valve mechanism on one side of the cylinder is a duplicate of that on the other side, I will merely describe the connections for one side.

1, is the valve stem to which is connected a crank arm 2, which is provided with a projection 3, adapted to be engaged by a lifting pawl 4, to rotate the valve stem 1, 85 to open the valve and admit pressure to the cylinder.

Loosely mounted on the outside of the valve stem bearing, is the ring 5, to which is connected the adjustable guard member 6, and the link 7. When this ring 5, with its guard, is in the position shown in Figs. 1 and 2, the lifting pawl 4, is free to engage the projection 3, and rotate the valve stem; but when the ring has been rotated 95 into the position shown in Fig. 3, the guard 6, is in alinement with the pawl 4, which will prevent its engaging projections 3, and allowing the admission valve to remain closed. The other end of the link 7, is pivotally connected to a cross head 8, secured to a rod 9 of non-magnetic material. This 10

rod 9, is mounted in bearings 10, 10, so as to slide therein. These bearings 10, 10, are secured to a bracket 11, which is rigidly secured to a portion of the steam chest of the engine.

A', is an electromagnet which is connected to the bracket 11, but is insulated therefrom. This electromagnet is provided with a soft iron core 12, surrounding the rod 9, and it is also provided with the usual pole pieces 13 and 24. Pivotedly connected to the pole piece 13, is the armature 14, which is provided with the adjustable stop 15 and the screw 16 at the end thereof. Secured to the pole piece 24, is an angular piece 26, which is provided with a hook 17.

Pivotedly secured to the cross head 8, is a spring catch 18, which engages the hook 17, when the rod 9 is in its elevated position, (the position shown in Figs. 4 and 5) which is the normal position of the rod 9, when the engine is running.

Secured to the bracket 11, is the switch B', having the contact fingers 20, and the swinging bridge piece 21, which will bridge the space, and electrically connect the fingers 20, when the same is pushed inwardly.

When the current is passed through the magnet A', the armature 14, will be attracted by the magnetic lines of force, and the screw 16, at the end of the armature will strike the spring catch 18, releasing it from the hook 17, which will allow the rod 9 to drop, carrying with it the cross head 8, which will rotate the ring 5 through the medium of link 7, and bring the guard 6, in line of movement of the lifting pawl 4, which will cut off the pressure to the cylinder. When this rod 9 is dropped, the cross head 8, will strike the bridge piece 21, and close the circuit through contact fingers 20 for the purpose hereinafter described.

When the engine is running, the various parts are in the position shown in the drawings, and if it is desired to stop the engine, the circuit is closed through the electro magnet A', releasing the rod 9, which will throw the guard 6, in alignment with the pawl 4, and close the switch B', and close the circuit through a circuit breaker or any other desired mechanism.

If the engine is protected by the stop in the drawings, the rod 9, is raised until the spring catch 18, engages the hook 17, which will remove the guards 6, from alignment with the lifting pawls 4, after which the throttle can be opened to start the engine.

It will readily be understood from the foregoing description, and the drawings, that I have devised an engine stop, which is under the control of the engineer from various points. Also a stop in which one engine of a series, or the whole plant, can shut down almost instantly. I have also provided means for closing an electric cir-

cuit through a switch arranged to close the circuit through any actuating mechanism when the engine stop is actuated.

I do not wish to limit myself to the details of construction, as the same can be changed without departing from the spirit and scope of my invention.

Having thus fully described my invention, what I claim as new, and desire to secure by Letters Patent is:—

1. An engine having a pressure cylinder, a piston in said cylinder, oscillating valves for controlling the admission of pressure fluid to said cylinder, actuating levers connected to said valves, projections on said levers, valve shifting devices movable about the axes of said valves for engaging the projections to open the valves to admit pressure to the cylinder, means to oscillate the valve shifting devices, guards movable about the axes of the valves and arranged to prevent the shifting devices engaging the projections, a gravity-actuated device movably mounted between said guards, links connecting the guards to the gravity-actuated device, and means for releasing the device to permit it to drop to move the guards into the path of movement of the valve-shifting devices; substantially as described.

2. An engine having a pressure cylinder, a piston in said cylinder, oscillating valves for controlling the admission of pressure fluid to said cylinder, actuating levers connected to said valves, projections on said levers, valve shifting devices movable about the axes of said valves for engaging the projections to open the valves to admit pressure to the cylinder, means to oscillate the valve shifting devices, guards movable about the axes of the valves and arranged to prevent the shifting devices engaging the projections, a gravity-actuated device movably mounted between said guards, links connecting the guards to the gravity-actuated device, and electrical means for releasing the device to permit it to drop to move the guards into the path of movement of the valve-shifting devices; substantially as described.

3. An engine stop of the character described, comprising oscillating valve-actuating devices, guards movable about the axes of the valve shifting devices arranged to be shifted into the path of movement of said valve-actuating devices, a gravity-actuated rod slidably mounted between the valve-actuating devices, links pivoted to the guards and the gravity-actuated rod, an electric magnet surrounding said rod, a spring catch pivotally connected to the rod, a projection arranged to be engaged by the catch, a pivoted armature, and means on said armature for releasing the catch; substantially as described.

4. An automatic stop for engines of the

- Corliss type having oscillating valves, a stem on each of said valves, a lever on each of said stems, lifting projections on said levers, an oscillating device for each valve having a lifting hook for moving the valves to their open positions, and oscillating guards movable about the axes of said valves arranged to be moved to points adjacent to said projections and into the path of the hooks to prevent the hooks from engaging the projections; substantially as described.
5. An automatic stop for engines of the Corliss type having oscillating valves, a stem on each of said valves, a lever on each of said stems, lifting projections on said levers, an oscillating device for each valve having a lifting hook movable about the axes of said valves for moving the valves to their open positions, oscillating guards arranged to be moved to points adjacent to said projections and into the path of the hooks to prevent the hooks from engaging the projections, a gravity-actuated device
- 10 for moving said guards, means for holding said gravity-actuated device in its elevated position, and an electro-magnet for releasing said gravity-actuated device; substantially as described.
- 15 6. An automatic stop for engines of the Corliss type, having oscillating valves, bell crank levers movable about the axes of said valves having hooks for actuating the valves, cam devices for engaging one of the levers of said bell crank for releasing the hooks, and guards movable about the axes of the valves arranged to be moved into the path of the hooks on the other levers to prevent said hooks actuating the valves; substantially as described.
- 20 In testimony whereof, I have affixed my signature in presence of two witnesses.

GEORGE HAMILTON McFEATERS.
